UNITED STATES PATENT OFFICE.

GUY J. GLENN, OF IMBLER, OREGON.

GRAIN-SHOCKER.

1,114,133.

Specification of Letters Patent. Patented Oct. 20, 1914.

Application filed April 20, 1914. Serial No. 833,226.

To all whom it may concern:

Be it known that I, GUY J. GLENN, a citizen of the United States, residing at Imbler, in the county of Union and State of Oregon, have invented certain new and useful Improvements in Grain-Shockers, of which the following is a specification, reference being had to the accompanying drawings.

10 This invention relates to certain improvements in grain shockers and has relation more particularly to a device of this general character especially designed and adapted to be secured to and travel with a grain binder of the usual construction; and the object of the invention is to provide a device of this general character having novel and improved means whereby the bundles, after being received from the binder, are delivered in proper position upon a shock forming table, such table being capable of movement to discharge such shock upon the ground.

25 The invention consists in the details of construction and in the combination and arrangement of the several parts of my improved device whereby certain important advantages are attained and the device is rendered simpler, less expensive and otherwise more convenient and advantageous for use, all as will be hereinafter more fully set forth.

The novel features of the invention will be carefully defined in the appended claims.

35 In order that my invention may be the better understood, I will now proceed to describe the same with reference to the accompanying drawings, wherein—

40 Figure 1 is a side elevational view of a shocker constructed in accordance with an embodiment of my invention the shock carrier being in discharge position; Fig. 2 is a top plan view of the device as disclosed in Fig. 1; Fig. 3 is a longitudinal vertical sectional view taken through Fig. 1 the shock carrier being in receiving position; Fig. 4 is a transverse sectional view taken substantially on the line 4—4 of Fig. 3; Fig. 5 is a top plan view of the table or carrier herein included; Fig. 6 is an enlarged detail view, partly in elevation and partly in section, illustrating a portion of the trip mechanism herein included; Fig. 7 is a sectional plan view of the parts illustrated in Fig. 6; Fig. 8 is an enlarged view in top plan, illustrating in detail the locking

means for the carrier or table, as herein disclosed, for maintaining such table in its elevated position; Fig. 9 is a sectional view taken substantially on the line 9—9 of Fig. 8; Fig. 10 is a fragmentary view in perspective, inverted, of a yoke included in the controlling mechanism for the sheaves as herein embodied; and Fig. 11 is a diagrammatic view of the crown included in such controlling mechanism.

As disclosed in the accompanying drawings, 1 denotes a frame provided with the traction wheels 2 and operatively engaged with the frame 1 is the forwardly directed draper 3 operatively connected with one of the traction wheels 2 through the medium of the gears 4. The draper is adapted to receive the bundles or sheaves as discharged from the binder of any ordinary or preferred construction and to carry the same rearwardly, and in order that the sheaves or bundles may assume a substantially upright position before delivered upon the table 5, I provide the side boards 6 of the frame 1 with the upwardly directed rearwardly inclined spring members 7 serving to operate in a manner which is believed to be self-evident.

Projecting upwardly from the frame 1 at 85 substantially its center is a post 8 and slidably engaged with such post 8 is the rearwardly directed dividing board 9 disposed at a predetermined distance above the table 5 and of a length substantially equal to the 90 length of the table.

The table or carrier 5, as herein disclosed, comprises a plurality of elongated spaced bars projecting rearwardly from the head 10 thereof, such head being herein shown as 95 substantially rectangular in form and swingingly engaged with the side boards 6 of the frame 1 through the medium of the links 11 whereby it will be readily perceived that the carrier 5 may be readily swung up 100 into substantial alinement with the draper 3 or dropped to the ground in order to discharge the shock formed thereon. In order to guide and support the carrier or table 5 in its movements, I provide the depending 105 slotted guides 12 engaged by the rear pivot pins 14 for operatively connecting the links and head 10. In order to maintain the table or carrier 5 in a position substantially alined with the draper 3, I provide one of the 110 side boards 6 with the latch member 15 directed therethrough and adapted to be

maintained against a side bar of the head 10 under the influence of the expansible member 16, herein shown as a coil spring embracing such latch and interposed between 5 the outer face of the side board 6 and a bracket 17, as is particularly shown in Figs. 8 and 9. The outer extremity of the latch 15 is provided with the longitudinally disposed elongated slot 18 through which projects an arm of a bell lever 19, the opposite arm of such lever 19 being engaged by the flexible member 20 leading to any predetermined point whereby it will be readily perceived that by exerting a pull upon the 10 lever 19 through the medium of the flexible member 20, the latch 15 will be disengaged from the head 10 and the table or carrier 5 permitted to drop under the influence of the sheaves or bundles thereon to the ground, as 15 indicated in Fig. 1, so that the shock formed thereon may be discharged.

The dividing board, hereinbefore referred to, is of a weight in excess of the table or carrier 5 and when such table or carrier 5 is released so as to fall to the ground, said 20 dividing board is adapted to move upwardly so that it will be released or disengaged from the tops of the bundles or sheaves and, as herein disclosed, this is accomplished by 25 connecting with such dividing board 9 adjacent its rear end a flexible member 21 passing up and around the sheaves 22, one of such sheaves being carried by the post 8 while a second sheaf is carried by a supplemental vertically disposed post 23, said 30 flexible member 21 being directed downwardly and operatively engaged with one of the links 11 whereby it will be readily perceived that as the carrier or table 5 drops 35 the dividing board 9 will be elevated. It will also be readily perceived that when the shock is discharged from the table or carrier 5, the weight of the dividing board 9 will serve to automatically return said table 40 or carrier to its operative position relative to the draper 3.

In order to maintain the bundles or sheaves against displacement from the table or carrier 5 during the forming of the shock 45 thereon, I find it of advantage to have the rearwardly disposed substantially parallel elongated spring members 24 disposed above the opposite longitudinal marginal portions of the table or carrier 5, one of such members being herein set forth as supported by the supplemental post 23 while the second of such spring members is supported by an additional post 25, as is believed to be clearly 50 shown in Fig. 4.

60 As the sheaves or bundles are carried rearwardly by the draper 3, they are delivered alternately upon opposite sides of the dividing board 9 and, as herein set forth, this position of the bundles or sheaves is accomplished through the rock levers 26 disposed

rearwardly of the draper, as shown in Fig. 2, and operatively connected with the vertical shaft 27 rotatably supported by the frame 1. The lower extremity of the shaft 27 has loosely mounted thereon the spaced gears 28 in mesh with an intermediate gear 29 fixed to an axle 30 with which one of the traction wheels 2 is operatively engaged, and the opposed faces of the gears 28 are provided with the clutch elements 31 with which is adapted to coact the clutch member 32 suitably keyed to the shaft 27 and capable of endwise movement thereon whereby it will be readily perceived that upon proper manipulation or movement of the clutch member 32, the shaft 27 will be caused to rotate in reverse directions.

In order that this alternate rotation of the shaft 27 may be accomplished in an automatic manner, I provide, as herein embodied, the wheel 33 rotating about a vertical axis, as indicated at 34, and operatively supported by a suitable bracket 35, and the upper peripheral marginal portion of the wheel 33 is provided with the upstanding annular undulated crown 36, on which is adapted to rest a rock arm 37 carried by a shaft suitably journaled in the adjacent end of the frame and provided with a second rock arm 38 operatively engaged with the 95 clutch member 32 whereby it will be readily perceived that as the wheel 33 is caused to rotate the high and low points *a* and *b*, respectively, will cause successive reverse movement of the clutch member 32 whereby 100 the shaft 27 will be caused to properly rotate in order to swing the arms 26 as desired. It is also to be observed that the crown 36 is provided intermediate each adjacent high point *a* and low point *b* with the straight 105 portion *c* whereby such clutch member 32 will be maintained in a neutral position, for reasons which will hereinafter be explained.

The upper face of the wheel 33 is provided with the teeth 39 adapted to be engaged by the fingers 40 produced at the free extremities of the fork 41 carried by the lever 42, such lever 42 being operatively engaged through the medium of the universal joint 110 43 with an arm of a bell lever 44 pivotally mounted upon the frame 1 and having its second arm overlying the draper 3 and in close proximity to the rear extremity thereof. This overlying arm of the bell lever 44 is adapted to be contacted with by the butt of a sheaf or bundle as carried rearwardly by the draper 3, and such contact will result in a rear movement of the lever 42 which will cause the wheel 33 to move so that the arm 115 37 will be engaged by either a high point *a* or a low point *b* of the crown 36 so that the clutch member 32 will be engaged with one of the clutch elements 31. After such bundle or 120 sheaf has passed over the overlying arm of 125 130

the bell lever 44, such lever will be retracted under the influence of the contractible member 45, herein disclosed as a coil spring, and such retractable movement of the lever 44 5 will result in a second finger 40 engaging a tooth 39 in the wheel 33 whereby it will be seen that the arm 37 will be caused to rest upon a straight portion *c* which will result in the clutch member 32 assuming a neutral 10 position.

In order that the grain which falls from the straw at the time of its delivery from the draper 3 to the carrier 5 may not be lost, I 15 position below the adjacent extremities of the draper 3 and the carrier or table 5 the pan 46, which serves for a purpose which is believed to be self-evident.

The lower portion of the post 8 is provided with a cone member 47 of predetermined 20 dimensions which is adapted to force the lower end portions or extremities of the sheaves or bundles outwardly or transversely of the table or carrier 5 so that the same will be disposed on the proper relative inclination 25 to maintain the shock.

From the foregoing description, it is thought to be obvious that a grain shucker constructed in accordance with my invention is of an extremely simple and comparatively 30 inexpensive nature and is particularly well adapted for use by reason of the convenience and facility with which it may be assembled, and it will also be obvious that my invention is susceptible of some change and modification 35 without material departure from the principles and spirit thereof and for this reason I do not wish to be understood as limiting myself to the precise arrangement and formation of the several parts herein 40 shown in carrying out my invention in practice.

Having thus fully described my invention what I desire to claim and secure by Letters Patent, is:

1. A device of the character described comprising a suitably supported draper, a carrier projecting rearwardly from such draper and upon which the same is adapted to deliver, and a plurality of upwardly disposed rearwardly inclined springs overlying the draper for causing the sheaves to assume a substantially vertical position.

2. A device of the character described comprising a suitably supported draper, a carrier projecting rearwardly from such draper and upon which the same is adapted to deliver, a plurality of upwardly disposed rearwardly inclined springs overlying the draper for causing the sheaves to assume a substantially vertical position, and means for causing a separation of the lower ends of the sheaves after being delivered to the carrier.

3. A device of the character described comprising a draper, a carrier coacting

therewith and upon which the same is adapted to deliver, and power driven means for causing the sheaves to be delivered alternately upon opposite sides of the carrier, said means including a controlling trip 70 adapted to be engaged by a sheaf.

4. A device of the character described including a suitably supported draper, a carrier upon which the draper is adapted to deliver, and a cone-shaped member interposed between the draper and carrier for causing a separation of the lower ends of the sheaves after being delivered upon the carrier.

5. A device of the character described comprising a draper, a carrier coacting with the draper and upon which the same is adapted to deliver, a vertically disposed shaft positioned intermediate the draper and the carrier, operating means for the shaft, and means for controlling the direction of rotation of the shaft, said last mentioned means being under control of a sheaf during its delivery from the draper to the carrier.

6. A device of the character described comprising a suitably supported frame, a draper operatively mounted upon the frame, a carrier supported by the frame and capable of movement relative thereto, a post projecting upwardly from the frame, a dividing board slidably engaged with the post, and an operative connection between the dividing board and the carrier whereby the same are caused to move in unison but in reverse 90 directions.

7. A device of the character described comprising a suitably supported frame, a draper operatively mounted upon the frame, a carrier supported by the frame and capable of movement relative thereto, a post projecting upwardly from the frame, a dividing board slidably engaged with the post, a guiding member carried by the upper portion of the post, and a flexible connection between the dividing board and carrier disposed over the guiding member of the post whereby the dividing board and carrier will be caused to move in unison but in reverse 100 directions.

8. A device of the character described comprising a draper, a carrier coacting with the draper and upon which the same is adapted to deliver, a vertically disposed shaft positioned intermediate the draper and the carrier, operating means for the shaft, means for controlling the direction of rotation of the shaft, said last mentioned means being under control of a sheaf during its delivery from the draper to the carrier, and means carried by the lower end portion of the shaft for causing a separation of the lower ends of the sheaves after being delivered upon the carrier.

9. A device of the character described

comprising a draper, a carrier coacting with the draper and upon which the same is adapted to deliver, a vertically disposed shaft positioned intermediate the draper and the carrier, operating means for the shaft, means for controlling the direction of rotation of the shaft, said last mentioned means being under control of a sheaf during its delivery from the draper to the carrier, 10 a cone-shaped member carried by the lower

extremity of the shaft for causing a separation of the lower ends of the sheaves after being delivered upon the carrier.

In testimony whereof I hereunto affix my signature in the presence of two witnesses. 15
